UNITED STATES PATENT OFFICE

HARRY L. COWLES, OF NEW YORK, N. Y.

INCINERATOR

Application filed November 7, 1925. Serial No. 67,509.

This invention relates to incinerators for destroying refuse and garbage, and its main object is to provide an improved apparatus of this class, particularly for the sizes adapted for apartment and household use as well as larger sizes for other uses. A special object is to provide convenient means for disposing of the ashes formed in the incinerator, without clogging the active parts of the same. Another object is to provide a lid or cover for the incinerator which prevents the escape of smoke and gases into the room during the normal operation of the incinerator. Still another object is to provide means for more thoroughly drying the refuse, garbage, etc. and to then ignite the same, and to provide an improved flue or flues for effecting equal and efficient distribution of hot gases and products of combustion during the incinerating operation.

The means I prefer to employ for accomplishing the above-named objects, together with other advantageous features of my improved incinerator, are illustrated in the drawings accompanying and forming part of this specification, and in which—

Figure 1 is a vertical section of my improved incinerator taken on the line 1—1 of Fig. 2.

Fig. 2 is a horizontal section taken on the line 2—2 of Fig. 1 but showing a rear corner in full or top plan.

Fig. 3 is a front elevation of the incinerator.

Fig. 4 is an enlarged view of a portion of Fig. 1.

Fig. 5 is a detail front elevation of a refuse holder or compartment taken midway of the incinerator.

Fig. 6 is a detail section taken on the line 6—6 of Fig. 1.

Fig. 7 is an enlarged front elevation showing the dumping handle and the locking means therefor.

Fig. 8 is a plan of the same also enlarged.

Fig. 9 is a vertical section of the upper part of a modified form of my invention.

Fig. 10 is a vertical section of the upper part of another form of my invention, and

Fig. 11 is a plan of the same.

Like characters of reference refer to like parts in all the figures of the drawings.

As illustrated in the drawings, my improved incinerator is constructed with a casing 1 mounted on legs 2 and provided with a hinged lid or cover 3, by means of which the refuse holders or compartments 4 and 5 can be filled with garbage and refuse. The casing 1 is provided with outer and inner walls 6 and 7 which I have hereinafter referred to as the double walls of the casing, and there is a passage 8 between said walls for the flow of cool air for reducing the temperature of the outside wall of the casing and for preventing the escape of products of combustion through the interstices between the casing and the edges of the lid or cover 3. The said lid is provided preferably with triple walls, such as 9, 10, and 11, held together by suitable means such as the screws 12, with suitable spacing members 13. There is an imperforate wall 14 at the side of each of the refuse holders or compartments 4 and 5. There is an encircling opening or air inlet 15 at the bottom of the casing 1, and a restricted and encircling air outlet 16 at the upper part of the casing. The said outlet 16 is formed by providing a member 17 of T cross section, superposed on the top edge of the outer casing wall 6, a member 18 of angular cross section at the top edge of the inner wall 7, and a flange 19 depending from the lower surface of the lid 3. The walls 6 and 7, T-member 17, and angle member 18 are secured together by bolts 20 and nuts 21, spaced by members 22. In the normal operation of the incinerator the flow of cool air takes the course indicated by the arrows 23 and effects the cooling of the exterior walls of the casing so that it is not much above the room temperature.

No smoke or products of combustion escape between the lid and the upper edges of the casing as there is a continual draft inwardly at that part, tending to carry smoke, air and gases into the outlet member 24. If for any reason the draft into the chimney through the member 24 becomes poor and the smoke does not readily escape, it will not escape under the lid 3 into the room but the

flow of combustion products and gases will be downward through the wall passage 8 in a direction reverse to the normal flow and thence through the inlet 15 and then upward into the interior of the incinerator as through the flues 25, 26. This action applies to slight coggings such as at first lighting the incinerator due to a cold chimney or a chimney with a weak draft.

The refuse holders or compartments 4 and 5 are constructed with side walls 27 and end walls 28 formed as separate members or grids, each consisting of substantially upright bars such as 29 with perforations such as 30. The said members 27 and 28 have lugs 31 and bolts 32 and nuts 33, by means of which they are secured together at the corners of the common flue 25. The grids or walls 27, 28, 28, and walls 14 thus form a rectangular refuse space which is completed when the three grids 27, 28, 28, are lowered into place.

Each of the end members 28 is provided with a bearing 34 which supports one of the trunnions 36 of the grid or grate 35 which forms the bottom or floor of the respective holder or compartment 4 or 5. The side members 27 are each provided with portions 37 forming a roof over the top of the common flue 25. The said portions 37 slope downwardly toward the interiors of the compartments 4 and 5, tending to cause the flow of hot air and combustion products to follow the course indicated by the arrows 38. The action of the hot air and products of combustion is to dry the upper parts of the contents of the compartments 4 and 5.

There are lugs 39 on the inner casing walls 7 which support the compartments 4 and 5, and their side wall members 27 come together at the middle of the incinerator along the roof portions 37 and also along partitions 40 preferably two in number and dividing the common flue 25 into three parts. The object of the partitions 40 is to prevent diagonal flow of hot air and products of combustion, so that all parts of the contents of the compartments will be given a uniform drying effect.

For effecting the drying and igniting of the contents of the compartments 4 and 5, I prefer to employ burners 41 for fluid fuel such as coal gas. The said burners 41 are each provided with side holes 42, top 43, inclined roof 44, inlet pipe 45 for mixed gas and air, mixer 46, gas supply pipe 47, and stop cocks 48. There is a pilot burner 49 midway between the two burners 41 and connected to the gas supply pipe 47 and provided with a stop cock 50. Each of the burners 41 is connected to its respective pipe 45 for supplying mixed gas and air, about midway of its length. With this construction the usual effect would be to cause a great flow of the mixture to the ends of the burner particularly the right hand one in Fig. 6 and with

too little of the supply going through the holes near the middle of the burner. To prevent this action and equalize the flow of the mixture, I provide an abutment such as 51 which deflects the flow so that a portion of the supply that would otherwise go to the right hand end is diverted into the holes of the burner near the middle thereof and also more of the supply goes to the left hand half of the burner, so that the flow of gas and air is equalized throughout the burner and a more uniform effect is attained.

The outer end of each of the front trunnions 36 of the grates 35 is square in cross section, so that it fits the socket 53 of a shaker 52 provided with a handle 54 and locking lugs 55 and 56. A latch 57 locks the grate 35 in its normal or level position by its locking portion 58 engaging with the lug 55 of the shaker 52, while the lug 56 engages the stop portion 59 on the stationary member 60. When the latch 57 is tripped, the shaker 52 can be oscillated by moving the handle 54 downwardly until the lug 55 engages the stop 61. A groove 62 in the shaker 52 is engaged by the V of the stationary member 60 and is thus held in proper position in the front wall 6 and also prevented from moving lengthwise.

There is an observation door 63, by means of which the internal conditions of the incinerator can be watched when incineration is taking place, and the lid 3 provides a most complete and convenient means of inspection when there is no combustion going on.

Fig. 9 illustrates a modified construction of the lid, double casing walls, and the restricted opening from the double wall air passages to the interior of the incinerator. It differs from that shown in Figs. 1 and 4 by having an angular member 64 in place of the T-member 17 and the depending flange 19 on the lid is nearer the interior of the incinerator.

Figs. 10 and 11 illustrate a form of the invention where the lid 3 does not cover the whole top of the incinerator but there is a fixed plate 65 forming the outer part of the incinerator top and provided with an opening 66 over which the lid 3' shuts. An inner plate 67 is provided which extends the wall passages 8 to meet the flange 19' of the lid so as to cooperate with it in forming a restricted passage for the incoming air.

Ordinarily I employ the burners 41 for effecting the drying and igniting of the refuse in the refuse holders or compartments 4 and 5, but I may also employ other means. For instance, I may fill the holders or compartments 4 and 5 with mixed refuse which would include waste papers, old magazines, and kitchen refuse and garbage, and then allow the mass to dry partially by the flow of air up through the incinerator from the open bottom of the same, through the grids 35, flues 25, 26, to the space over the compartments 4

and 5, thence to the outlet 24 into the chimney flue. If the chimney draft is good, the drying effect will be very satisfactory and after a short time a lighted paper can be inserted into the incinerator, preferably under one or both of the compartments 4 and 5, and ignition will promptly take place and combustion of the masses in the compartments 4 and 5 will follow without the use of gas or other additional fuel. It is not always necessary to light from below in such cases especially if there is much dry paper in the incinerator, as in that case it can be very satisfactorily lighted by dropping a lighted paper from above the compartments, first raising the lid if the same is used.

The incineration chamber or destructor chamber is the interior chamber 100 of the casing, whereof the upper parts are utilized for refuse destruction or incineration, and the lower parts for igniting the refuse in the construction illustrated and also for removal of ashes. The removal of ashes which collect in the lower parts of the holders or compartments 4 and 5 may be effected in any suitable manner as by placing an ash pan on the floor under the grid or grids 35 and dumping the latter by means of the handle or handles 54.

It is evident that the form and arrangement of the different parts may be modified and changed in various ways and I do not therefore confine myself to the exact details of construction and arrangement here shown.

What I claim is:—

1. A refuse incinerator embodying a casing, and a refuse holder therein having upright walls which include two end grids, an intermediate grid, and a fourth wall juxtaposed to and supported by but separate from the casing, said walls secured together within the casing and said intermediate grid forming one wall of an upright flue immediately adjacent the refuse holder up which products of combustion can pass.

2. A refuse incinerator embodying a casing, and a refuse holder therein rectangular in cross section having upright walls which include two end grids, an intermediate grid, and an imperforate plate adjacent to and supported by the casing, said walls secured together within the casing, and means below the refuse holder for effecting the drying and igniting of the contents thereof, said intermediate grid forming one wall of an upright flue immediately adjacent the refuse holder up which products of combustion from said means can pass.

3. A refuse incinerator embodying a casing, and a refuse holder therein having four upright walls which include two end grids, an intermediate grid, and an imperforate plate adjacent to and supported by the casing, said walls secured together within the casing, and an independently movable flat grid trans-

verse to said plate and grids, secured to the end grids only and forming the floor of the refuse holder, said intermediate grid forming a separating wall of an upright flue adjacent to said refuse holder.

4. A refuse incinerator embodying a casing, and a refuse holder therein having upright walls which include two end grids each having a centrally-disposed bearing in the lower part, which bearings are alined to a common axis, an intermediate grid connecting the end grids at one side, and an imperforate plate connecting them at the other side, and a floor grid having trunnions one at each end by which it is supported and pivoted in said bearings, said intermediate grid forming one wall of an upright flue system extending across the incinerator substantially parallel to the axis of the floor grid.

5. The combination of a casing, a refuse holder therein rectangular in cross section, having upright walls which include two end walls each having a bearing, which bearings are substantially on the same axis, and an intermediate apertured wall, there being an upright flue immediately adjacent to said intermediate wall, a flat grid transverse to the upright walls, forming the floor of the refuse holder, and having a trunnion at each end whereby it is supported and journaled in said bearings, an elongated burner having a plurality of openings for burning fluid fuel, below said trunnions, and a roof portion over said burner alined with and below the trunnions and covering said burner openings.

6. A refuse incinerator embodying a casing, a refuse holder structure therein having upright walls which include two end grids, an intermediate grid, and a fourth wall adjacent to but separate from the casing, said walls secured together within the casing and said intermediate grid forming one wall of an upright flue system extending across the incinerator, and means whereby said refuse holder structure is supported in the casing.

7. A refuse incinerator embodying a casing having outer and inner walls, a refuse holder structure in said casing having upright walls which include two end grids, an intermediate grid, and a fourth wall juxtaposed to but separate from the casing, said intermediate grid forming one wall of an upright flue system extending across the incinerator, and means on the inner walls of the casing for supporting the refuse holder structure.

8. A refuse incinerator which includes a casing having two substantially parallel side walls, a refuse container structure within said casing having a plurality of separate upright grids including a grid substantially parallel to the casing side walls in horizontal section and forming a wall of an upright flue system extending across the incinerator, and means

for supporting the container structure on the two casing side walls.

9. A refuse incinerator embodying a casing having two upright and substantially parallel side walls, a refuse holder structure in said casing having upright walls which include two end grids, an intermediate grid, and a fourth wall adjacent to but separate from the casing, said intermediate grid forming one wall of an upright flue system extending across the incinerator, and means on the casing side walls for supporting the refuse holder structure.

10. A refuse incinerator embodying a casing having outer and inner walls and including two inner upright side walls, a refuse holder structure in said casing having upright walls which include two end grids, an intermediate grid, and a fourth wall adjacent to but separate from one of said casing side walls, and means on said casing inner side walls for supporting the refuse holder structure.

11. A refuse incinerator embodying a casing, and two oppositely disposed refuse holders therein each having upright walls including two end grids and an intermediate grid forming a side wall of its refuse holder, said intermediate grids also forming walls of a flue system having a portion between the refuse holders and each provided with a plurality of vertical ribs said ribs being oppositely disposed on the respective intermediate grids and the ribs of each such grid meeting those of the other such grid to form partitions in said flue portion.

12. A refuse incinerator embodying a casing having two side walls, two refuse holders within said casing each such holder including two end grids, an intermediate grid, and a fourth wall adjacent to a casing side wall but separate from the same, said intermediate grids each forming a wall of an upright flue system between them extending across the interior of the incinerator, and means on said casing side walls for supporting said refuse holders.

13. A refuse incinerator embodying a casing having outer and inner walls including two side walls, refuse holder structure including two refuse holders each holder having two end grids, an intermediate grid, and a fourth wall adjacent to but separate from the casing side wall at its respective side, said intermediate grids each forming a wall of an upright flue system between them extending across the interior of the incinerator, and means on said inner casing side walls for supporting the refuse holder structure.

14. An incinerator embodying a casing having outer walls provided with horizontal lid-supporting portions, a lid hinged to one side of the casing adjacent said lid-supporting portions and normally resting on the latter, inner walls secured to said casing

whereby a passage is formed having an encircling opening at the upper part, a refuse holder within said casing and adjacent an upright flue extending across the interior of the incinerator, and a smoke outlet pipe passing through an outer and an inner casing wall below said encircling opening but above the refuse holder and flue.

15. A refuse incinerator embodying an outer casing having two side walls, and a refuse holder within the casing having upright walls which include two end grids, an intermediate grid, and a fourth wall parallel and adjacent to one of said casing side walls, said holder walls secured together within the casing and said intermediate grid forming one wall of an upright flue extending across the incinerator and up which products of combustion can pass.

16. A refuse incinerator embodying an outer casing having two side walls, two refuse holders within said casing each such holder including two end grids, an intermediate grid, and a fourth wall adjacent to one of the casing side walls, connected with but separate from the outer casing, said intermediate grids each forming a wall of an upright flue system extending across the incinerator, and means on the casing side walls for supporting said refuse holders.

Signed at New York, in the county of New York, and State of New York, this 27th day of October, 1925.

HARRY L. COWLES.
